[57] ABSTRACT

A basketball rebound dome in the shape of a convex surface member having a plurality of raised protuberances thereon against which a basketball may strike to cause erratic bouncing is held within the rim of a basketball goal by a plurality of radially extending clamps.

BASKETBALL REBOUND DOME

This application is a continuation-in-part application of our pending application Ser. No. 818,572, filed Apr. 23, 1969, now U.S. Pat. No. 3,795,401.

This invention relates to attachment devices for game equipment, and more particularly to a device for basketball practice.

It is therefore the main purpose of this invention to provide a basketball rebound dome which will be attached by clamp means to a basketball hoop and will serve to develop basketball players' rebound ability with a basketball.

Another object of this invention is to provide a basketball rebound dome which will be moulded or formed in a suitable way so as to have up-raised hemispherical surfaces, which when the basketball strikes one of these surfaces, it will cause the basketball to rebound in a random fashion.

A further object of this invention is to provide a rebound dome of the type described, which will have a plurality of clamp members secured to the rim of the device to clampingly engage the hoop attached to the backboard so as to render the dome device stationary while also allowing it to be easily removed after a practice.

Other objects of this invention are to provide a basketball rebound dome which is simple in design, inexpensive to manufacture, rugged in construction, easy to use and efficient in operation.

These and other objects will become readily apparent upon a study of the following specification together with the accompanying drawings wherein:

FIG. 1 is a perspective view of the present invention shown secured to a basketball hoop with a basketball shown in phantom lines;

FIG. 2 is a fragmentary, horizontal view of the device shown in elevation and in section;

FIG. 3 is a partially broken perspective view (similar to FIG. 1) of a modification of the invention wherein the bumps are three-sided pyramids with triangular bases;

FIG. 4 is a fragmentary perspective view of the invention wherein the bumps are four-sided pyramids with square bases;

FIG. 5 is a sectional view taken on the line 5—5 of FIG. 4;

FIG. 6 is a fragmentary perspective view of the invention wherein the bumps are upwardly projecting, cylindrical prongs;

FIG. 7 is a fragmentary perspective view of the invention wherein the bumps are elongated triangular-shaped prisms;

FIG. 8 is a fragmentary perspective view of the invention wherein the bumps are cones;

FIG. 9 is a fragmentary perspective view of the invention wherein the bumps are of a faceted configuration having a plurality of sides;

FIG. 10 is a sectional view similar to FIG. 5 wherein the convex outer surface of the rebound dome is an irregular surface;

FIG. 11 is a fragmentary perspective view of the invention wherein the bumps are of irregular configuration;

FIG. 12 is a fragmentary perspective view of the invention wherein the bumps are upstanding, rectangular solids;

FIG. 13 is a fragmentary perspective view of the invention wherein the bumps are upstanding, triangular prisms;

FIG. 14 is a fragmentary perspective view wherein the bumps are upstanding, hexagonal projections;

FIG. 15 is an elevational, sectional view of the invention wherein the convex outer surface of the rebound dome has a single bump thereon of hemispherical configuration, and

FIG. 16 is a fragmentary perspective view of the invention wherein the rebound dome is shown with different types of bumps thereon.

According to this invention, a basketball rebound dome 10 is concave on its underside 11 and is provided with a plurality of spaced apart and raised protuberances, such as hemispherical surfaces 11' which when struck by basketball 12 will cause ball 12 to rebound in a random fashion so as to develop a basketball player's skill in handling rebounds. To the rim of rebound dome 10, extends a plurality of radially spaced apart clamps 14, the opening 15 of clamps 14 receiving portions of the hoop 16 which is secured to the backboard 17.

In use, the basketball 12 when shot by the player above the basketball hoop 16, will descend, striking any one of the plurality of hemispherical surfaces 11', the inherent shape of surfaces 11' causing the basketball 12 to rebound in any direction, thus developing the player's skill at handling rebounds.

It will be understood that various sizes, types, modifications and different configurations of the bumps or protuberances 11' may be used as shown in FIGS. 3-15.

In FIG. 3, for example, the convex upper, outer surface 20 of the rebound dome has a plurality of bumps 21 thereon which are three-sided pyramids with triangular bases.

In FIGS. 4 and 5, the bumps 24 are four-sided pyramids with square bases.

In FIG. 6, the bumps 26 are upwardly projecting prongs.

In FIG. 7 the bumps 28 are elongated triangular-shaped prisms.

In FIG. 8 the bumps 30 are cones.

In FIG. 9 the bumps 32 are of a faceted configuration of many sides.

In FIG. 10 the convex upper outer surface 36 of the rebound dome is of irregular configuration.

In FIG. 11, the convex outer surface 40 has a plurality of bumps 41 thereon of irregular configuration.

In FIG. 12, the bumps 44 are upstanding rectangular solids.

In FIG. 13, the bumps 46 are upstanding triangular prisms.

In FIG. 14, the bumps 48 are upstanding hexagonal projections.

In FIG. 15, the convex outer surface 50 has a single hemispherical bump 52 thereon, which may be positioned anywhere on such surface 50.

In FIG. 16, the convex outer surface 54 has a plurality of different type bumps thereon such as the prong 26, the cone 30 and the pyramid 24.

In essence, the invention contemplates the use of any type or shape of bumps positioned in irregular or in symmetrical pattern on the convex outer surface. For example, the bumps 28 of FIG. 7 are positioned on the convex surface member in substantially symmetrical

pattern, and the bumps 41 of FIG. 11 are disposed on the convex member in irregular pattern.

What is claimed is:

1. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising a three-sided pyramid with a triangular base.

2. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising a four-sided pyramid with a square base.

3. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising an upwardly projecting cylindrical prong.

4. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising an elongated triangular shaped prism.

5. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising a cone.

6. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising a faceted configuration having a plurality of sides.

7. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising an upstanding rectangular solid.

8. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising an upstanding triangular prism.

9. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising an upstanding hexagonal projection.

10. A basketball rebound dome device for detachable securement to the top of a basketball hoop comprising an upwardly convex surface member having at least one raised protuberance thereon causing erratic bouncing of a basketball striking thereagainst, and means for detachably securing the convex surface member to the top of an associated basketball hoop, said at least one protuberance comprising a plurality of bumps of different configurations.
